United States Patent Office

Des. 219,093

Patented Oct. 27, 1970

219,093

INDICATOR PLAQUE

Frank E. Bayne, Jr., and Lois Bayne, both of 134 4th St.,
Aspinwall, Pa. 15215

Filed Aug. 27, 1969, Ser. No. 18,864

Term of patent 14 years

Int. Cl. D20—03

U.S. Cl. D96—12

Fig. 1.

Fig. 2.

FIG. 1 is a front elevational view of the indicator plaque embodying our new design, the rear being plain and unornamented; and

FIG. 2 is a side elevational view thereof.

We claim:

The ornamental design for an indicator plaque, as shown and described.
